COMBINATION LEG AND TOWEL BAR UNIT FOR LAVATORY

Cecil W. Farrar, Buffalo, N. Y., assignor to Case Manufacturing Corporation, Robinson, Ill., a corporation of New York

Application November 23, 1956, Serial No. 43,909

Term of patent 14 years

(Cl. D4—2)

Fig. 1 is a perspective view of a combination leg and towel bar unit for lavatory, showing my new design, with a basin shown in broken lines for illustrative purposes only.

Fig. 2 is a side elevational view of the unit looking toward the right of Fig. 1.

Fig. 3 is a front end view of the right hand portion of the unit as shown in Fig. 1.

The dominant features of my new design are shown in solid lines.

I claim:

The ornamental design for a combination leg and towel bar unit for lavatory, substantially as shown and described.
